HANDLE FOR HAND GRENADES

Georg Erdmann, Berlin, Germany

Application September 28, 1937, Serial No. 166,146
In Germany July 6, 1936

2 Claims. (Cl. 102—29)

This invention relates to a handle for hand grenades with tear-off fuse.

Such handles consist of three parts, namely a connecting piece, with a screw thread for screwing on the container for the bursting charge, a handle and a closure cap.

In the hand grenades with handles hitherto used the connecting piece consists of a thin walled metallic under portion, which is to be slipped over the wooden handle of the hand grenade, and a thick walled upper portion, perforated at the tip and provided with a screw thread, onto which the actual grenade is screwed. The upper portion, the under portion and the handle are connected with one another by means of four or more screws. The handle through which the tear-off fuse goes, is hollow and consists of impregnated beechwood, while the closure cap, which is placed upon its under portion, is of sheet zinc. Such a hand grenade handle therefore comprises two screw connections between wood and metal, and there is therefore always a great risk that moisture may get in, as a result of which the grenade would become useless. Efforts have been made to obviate this disadvantage by selecting a timber of suitable density which is not liable to crack, namely beech, by impregnating this wood, and by introducing liquid sealing means at the point where the connecting piece of the hand grenade is screwed to the wooden handle. In particularly wet weather, however, and under other unfavourable external circumstances, the desired success is not uniformly attained, so that 10% or more of the grenades still miss fire.

Furthermore the cost of the hand grenade handle becomes quite considerable owing to the difficult treatment of the wood and a particularly careful and massive construction of the connecting piece.

Now according to the present invention the connecting piece, the handle and the closure cap of the hand grenade, are made of artificial resin. For this purpose there come primarily into consideration the condensation products of phenol and its homologues with formaldehyde and its homologues, and also urea formaldehyde resins, as well as other synthetic artificial resins, which can be forced into suitable moulds by pressure and heat.

With the resins, fibrous substances may be mixed for the purpose of increasing their tenacity.

In selecting this material for the hand grenades it is possible to press the connecting piece, pro-

vided with reinforcing insertions, in one piece, instead of having to make it in two pieces. The invention is illustrated by way of example in the accompanying drawing, in which Figures 1, 2 and 3 show respectively the connecting piece, the handle proper or shank member, and the cap, the left-hand half of each figure being in axial section and the right-hand half being an outside view.

In the drawing, 1 is the connecting piece, 2 the shank member or handle proper, and 3 the cap. The lower portion 4 of the connecting piece is made somewhat thicker than has hitherto been usual when employing sheet metal. This member is secured to the handle not by screwing but is welded thereto by means of heat.

The making of the rather long handle, which is shown in its natural proportions in the drawing, is effected by forcing suitably shaped upper and lower dies from opposite ends into the heated mass of artificial resin, placed in suitable moulds, and provided with reinforcing insertions. The handle thereby acquires the shape illustrated in the drawing, with a screw thread at the lower end. A thin partition remaining in the centre is mechanically removed by pushing it out.

The closure cap 3 is also pressed out of one piece. Its connection with the handle is completely watertight, because the screw threads of the artificial resin handle do not warp like those of a wooden handle under the influence of moisture.

In the central portion of the handle there may also be impressed in the course of manufacture, a roughened pattern 5, in order that the hand grenade may not slip when being thrown, even if it is wet.

Quite short tubes of artificial resin have already been made by employing upper and lower dies, but from this the idea has not yet arisen that the manufacture of such long handles as are required for hand grenades with tear-off fuses would be possible by the use of such dies.

Artificial resin has already been suggested for the butts of firearms, but hand grenade handles and their accessories have to fulfil practical requirements of quite a different nature from those of firearms.

Thanks to the adoption of artificial resin the manufacture of hand grenade handles with connecting piece and closure cap is reduced to half the cost. Beechwood of the best quality is saved, and failures arising from the penetration of moisture, which amount to about 12% even when impregnated beechwood is employed, are entire-

ly obviated, and this is a point of the utmost importance.

For the production of the handles and accessories the most varied artificial pressed substances may be employed, with or without reinforcing insertions. A reinforcing insertion 6 is shown in Figure 2. The thickness and the form of the walls, and also of the accessories, can be adapted to the current requirements of the military authorities.

The closure cap may be connected with the handle in some way other than by screwing.

According to the present invention the handles and accessories of hand grenades without tear-off fuses may also be made of artificial resin.

I claim:

1. A handle for hand grenades, more particularly those with tear-off fuses, comprising a shank member, pressed out of artificial pressed material, an externally screw-threaded connecting piece made of artificial pressed material and non-releasably welded in a water-tight manner to the upper end of the shank member, and

adapted to accommodate an internally screw-threaded container for a bursting charge, an external screw thread formed on the lower end of the shank member by pressure, and a closure cap pressed out of artificial material screwed directly on to the thread at the lower end of the shank member.

2. A handle for hand grenades, more particularly those with tear-off fuses, comprising a shank member, pressed out of artificial pressed material with reinforcing insertions, an externally screw-threaded connecting piece made of artificial pressed material with reinforcing insertions and non-releasably welded in a water-tight manner to the upper end of the shank member, and adapted to accommodate an internally screw-threaded container for a bursting charge, an external screw thread formed on the lower end of the shank member by pressure, and a closure cap pressed out of artificial material screwed directly on to the thread at the lower end of the shank member.

GEORG ERDMANN.
